BURIAL CASKET CONSTRUCTION

George C. Hillenbrand, Batesville, Ind., assignor to The Batesville Casket Co., Inc., Batesville, Ind., a corporation of Indiana

Application February 11, 1957, Serial No. 639,262

7 Claims. (Cl. 27—14)

This invention relates to an improved construction for burial caskets. In general, a burial casket is constituted by a main body portion and one or more top sections which are hinged to the body portion. At the present time, caskets are generally classified as full couch caskets and cut-top caskets which include half couch caskets. Caskets of the first type are provided with a single top which is hinged to the body portion so that it may be opened or closed at will. The second type is provided with two independently hinged top sections whereby, if desired, only part of the casket is opened for display purposes. In either case, the casket top, or top section, is constituted by a rigid structural section which is conventionally dome-shaped and an interior which is upholstered to provide a pleasing appearance. Further, it is now particularly desirable to provide a very strong top structure in order to permit the effective use of sealing gaskets on caskets of the type which are generally known in the trade as "sealers." Both the half couch and full couch sealer caskets are disclosed in United States Patent to Purkiss No. 2,284,921. These are but two of many types of caskets to which the invention is applicable. In general, it is applicable to any casket construction having a body and a top, which top may comprise one or more sections.

Until relatively recently, it was universal practice to upholster the inside of the casket top, if intended for display purposes, with upholstering padding and a cover of silk, rayon, nylon, or the like, just as if the display were an article of furniture such as a couch or chair. This upholstering operation proved very expensive in that it required much material and time as well as highly skilled labor. Recently it has become practicable to substitute a fabric-covered sheet material interior unit or insert in the casket top in place of the conventional upholstering. Such an interior unit is disclosed in United States Patent No. 2,664,615, issued January 5, 1954.

In the past, it has been conventional to place a wooden frame about the margin of the hinged top of the casket both to stiffen the top and to permit tacking of the upholstery or the sheet material insert in place in the top of the casket. The use of these wooden frames is undesirable in that their construction in the casket top does not readily lend itself to quantity production methods, the frame provides less than the desired rigidity and the operation of tacking the upholstery or interior unit in place is tedious and requires substantial hand labor.

The casket top of the present invention is provided with a novel, dual-purpose channel member which takes the place of the wooden frame and at once provides a top structure which is very rigid and which facilitates the attachment of an ornamental interior unit which is fabricated from sheet material. The details of the construction of the preferred sheet material interior unit or insert are disclosed in co-pending application, Serial No. 639,368, filed February 11, 1957, for "Casket Interior Unit."

2

The nature of the invention will be better understood by reference to the accompanying drawing in which:

Figure 1 is a plan view of the interior of the domed casket top section.

Figure 2 is a plan view of the sheet material insert adapted to be placed in the top section which is disclosed in Figure 1.

Figure 3 is a sectional view showing the marginal flange of the top section and the margin of the sheet material insert prior to attachment of the insert to the top section.

Figure 4 is a sectional view showing the edge of the sheet material insert attached to the flange of the top section.

Figure 5 is a broken view which shows the construction of the preferred sheet material interior unit.

Referring to the drawing, top section 1 is provided with the conventional dome-like configuration 2 and an internally projecting marginal flange 3 which occupies a horizontal position when the casket top is down. About the edge of marginal flange 3, channel members 4 are disposed by spot welding, seam welding or other means, as at 5 and by tack welding at the corners of the channel members 4, as at 6. Thus, the dome-shaped top section is provided with a structurally reinforced margin which is rectangular. Hinges (not shown) are attached to one side of marginal flange 3 and on the opposite side of the top section apertures 7 are provided for locking down the top section.

The reinforcing channel structure is constituted by four individual lengths of sheet metal. Each length is bent to provide a face or strip portion 8 which is welded to the inner side of the inturned flange 3, a flaring, substantially U-shaped channel section 9 which projects inwardly of the marginal flange 3 and a reinforced inner margin 10 which is provided by the inner edge of the channel member which is bent upon itself as disclosed in Figures 3 and 4. It is also to be particularly noted that the channel members are secured within the marginal flange in such a manner that the edge of the marginal flange extends beyond the outer flange of the channel to provide a detent edge 11.

The sheet material interior unit or insert, which is more particularly disclosed in co-pending application, Serial No. 639,368, filed February 11, 1957, comprises a top panel 12, side frame members 13, which are preferably bowed, and lock tabs 14 which fit into the channel of the sheet metal frame. Individual lock tabs are shown at the sides of the insert; however, it will be appreciated that the tabs may be continuous at each of the four sides of the unit. More particularly, the insert is constituted by sheet material such as cardboard members 15 which are held together by staples 16 or by stitches or the like, and which are covered by a lining cloth 17 and a surface fabric 18 which may be silk, rayon, nylon or some other fabric having a pleasing and ornamental appearance.

Ordinarily, an adhesive is used for securing the fabrics to the cardboard or paperboard backing and to each other.

The margin of the sheet material insert may be secured to the channel which rigidifies the top section by any desired means but preferably the construction is utilized which is particularly disclosed in Figures 3 and 4. The preferred form of the invention provides for the utilization of a double bend of the sheet material insert adjacent to its margin whereby the margin of the sheet material insert is nested in the channel with the marginal tabs of the sheet material insert retained in locked position in the channel by the reverse bend of the lock tabs 14 which engage detent 11.

While the construction described is adequate to hold the sheet material insert in the sheet metal casket top, the construction as so far described leaves the joint or lock visually exposed, which is undesirable in an orna-

mental structure such as a casket top. Hence, ornamental plastic or rubber beading 19 is utilized to cover the junction of the margin of the sheet material insert and the margin of the inturned flange of the casket top. As disclosed in Figure 4, the beading comprises the exposed ornamental head 20, the wedge-shaped insert 21, which fits compactly into the flaring channel, and the detent groove 22 into which detent 11 fits. The beading is readily inserted in place by virtue of the fact that it is constituted by a plastic material which is adapted to accommodate itself to the configuration of the channel after the margin of the interior unit has been inserted in the channel.

In the shop terminology of the casket industry, this particular sheet material insert is called a "snap-in dish" because it can be readily snapped in the channel and the ornamental beading can also be snapped into the channel thus both visually obscuring the junction of the dish and its frame and insuring the tightness and permanence of the lock between the margin and the snap-in dish and the channel.

The advantages of the disclosed construction are numerous. In the first place, the reinforcing channel provides an improved casket top structure which has far greater rigidity than the ordinary casket top which is fabricated with a wooden frame and this rigidity is particularly desirable if the casket is of the sealer type. Furthermore, the inwardly turned flanges are maintained in true planar condition so that they present flat mating surfaces to sealing devices which may be located on the margin of the body of the casket. As pointed out before, this sealer type of casket requires a very rigid top section because the top section must be drawn evenly into close contact with the top of the body section of the casket in order to provide a seal between the top section and the body of the casket. In the second place, the use of the sheet material insert saves a great deal of expense in labor and materials in comparison with the conventional operation of upholstering the interior of the top section by conventional methods. In the third place, the snap-in lock between the margin of the insert and the channel of the top provides a connection which is both secure and ornamental and which requires no laborious hand work or specialized skill to consummate. Additionally, the decorative insert is held in place solely by reason of its engagement with the reinforcing channel. Therefore, the means which are provided to hold it in place places no restriction upon its design, shape, or construction other than that it have some means at its outer marginal edge to engage in the channel. Hence, this invention provides a casket which is not only structurally superior to conventional caskets but which may be fabricated in quantity production with minimum expenditure of labor and materials.

While the channel members herein are shown in relation to a casket shell section constituting a top, it can also be used in relation to the shell section constituting a body of a casket, with the channel being disposed to receive decorative lining material for the interior of the casket body.

Having described my invention, I claim:

1. A casket top comprising a sheet metal structure adapted to be fastened to a casket body, said top provided with an internally extending flange which is in horizontal position when the casket top is in closed position, and a reinforcing channel secured to said flange, said channel projecting inwardly of the flange and extending all of the way around the casket top, a sheet material ornamental insert having its margin disposed in said channel, and detent means associated with said channel and engaging the margin of said insert for securing said margin in said channel.

2. A casket top comprising a sheet metal structure adapted to be fastened to a casket body, said top pro-

vided with an internally extending flange which is in horizontal position when the casket top is in closed position and a reinforcing channel secured to said flange, said channel projecting inwardly of the flange and extending all of the way around the casket top, an ornamental sheet material insert having its margin disposed in said channel, and means for securing said margin in said channel.

3. A casket top comprising a sheet metal structure adapted to be fastened to a casket body, said top provided with an inwardly extending flange surrounding the inside of the top which is in horizontal position when the casket top is in closed position, reinforcing channel members, each reinforcing channel member comprising a planar strip portion having an integral channel portion extending along one side edge thereof, the respective reinforcing channel members secured to the inner face of the internally extending flange and being coextensive therewith, the channel portions of the members disposed to the inside of said internally extending flange and opening downwardly in positions to receive the outer marginal edges of a casket top lining, and means in the channel to lock the marginal edges of said top lining therein.

4. A casket top comprising a sheet metal structure adapted to be fastened to a casket body, said top provided with an internally extending flange which is planar and which is in horizontal position when the casket top is in closed position, a reinforcing channel extending all of the way around the inwardly extending flange adjacent flange adjacent to the inward margin thereof to rigidify the casket top, a sheet material ornamental insert for said casket top having its marginal edges inserted into said channel, and means securing said marginal edges in said channel.

5. A casket top comprising a sheet metal structure which has a continuous flat flange extending marginally around its underside, rigid channel portions immovably fixed to the flange adjacent to the inner edges thereof, a decorative insert of sheet-like material of a size to substantially fill the space between the inner edges of the flat flange, tabs at the marginal edges of said insert engaged in said channel portions, and means to lock said tabs in said channel portions to hold said insert in place in the top.

6. A casket top comprising a sheet metal structure adapted to be fastened to a casket body, said top being provided with an internally extending flange which is in a horizontal position when the casket top is in a closed position, channel members mounted on the interior edge of said inwardly turned flange with the edge of the flange projecting beyond the outer wall of the channel to provide a detent, and a sheet material ornamental insert provided with marginal tabs, said marginal tabs tucked into the channel and retained therein by the detent.

7. A casket top comprising a sheet metal structure adapted to be fastened to a casket body, said top provided with an internally extending flange which is in a horizontal position when the casket top is in closed position, channel members mounted on the interior edge of said inwardly turned flange with the edge of the flange projecting beyond the outer wall of the channel to provide a detent and a sheet material ornamental insert provided with marginal tabs, said marginal tabs tucked into the channel and retained therein by said detent, and ornamental beading disposed in said channel to cover the joint between the flange and insert and to insure the permanence of the lock between the top and insert.
